UNITED STATES PATENT OFFICE.

SAM EVERSEN, OF BILLINGS, MONTANA.

DOOR-ACTUATING MECHANISM FOR ELEVATORS.

1,313,591.

Specification of Letters Patent.

Patented Aug. 19, 1919.

Application filed June 18, 1918. Serial No. 240,575.

To all whom it may concern:

Be it known that I, SAM EVERSEN, a citizen of the United States, residing at Billings, in the county of Yellowstone and State 5 of Montana, have invented certain new and useful Improvements in Door-Actuating Mechanism for Elevators, of which the following is a specification.

This invention relates to door actuating 10 mechanism for elevators, having for its primary object to provide means of this character of simple and improved construction which operates automatically upon the ascent or descent of the elevator car to open or 15 close the door leading into the elevator shaft.

A further object of the invention is to provide a mechanism which is so constructed and arranged that the door in the shaft will be opened either when the car is ascending 20 or descending and will be maintained in such position so long as the car remains stationary in the doorway.

A further object of the invention is to provide a mechanism of the character stated 25 which operates automatically when the car leaves the doorway to release the door to allow the same to close.

Still further and particular objects are to provide a door actuating mechanism for 30 elevators of extremely simple construction, which may be quickly and easily applied to the elevator, which is composed of comparatively few simple and readily assembled parts, the various parts being so constructed 35 and assembled as to minimize the opportunity for wear or breakage, and which will prove thoroughly reliable in practice.

With these objects in view together with others which will appear as the description 40 proceeds, the invention resides in the novel formation, combination and arrangement of parts, all as will be described more fully hereinafter, illustrated in the drawings and particularly pointed out in the claims.

45 In the drawings:—

Figure 1 is a vertical sectional view taken through a conventional elevator shaft and car, and illustrating the application of a door actuating mechanism constructed in accordance with the invention.

Fig. 2 is a front elevation of the car equipped with the operating apparatus,

Fig. 3 is a top plan view of the car and the apparatus,

Fig. 4 is a plan view of one of the door 55 actuating weights, and

Fig. 5 is a detail perspective view of one of the tripping members carried by the car.

Referring now more particularly to the drawings, 6 indicates a car or lift of conventional construction, mounted for vertical sliding movement within the shaft and slidably arranged upon the side rails 7. This car has uprights 8 at its sides and the uprights are connected at their upper ends by the 65 cross bar 9 to which the lifting apparatus may be attached.

One of the doors opening into the shaft for the elevator is indicated conventionally at 10 and is vertically slidable in the guideways 11 at the sides of the doorway. The door is equipped with the balance weights 12 movable vertically in suitable pockets at the sides of the doorway and connected to the door by the ropes or cables 13. It will 75 be understood that these balance weights together are of slightly less weight than the door itself.

The car 6 is provided near its upper end at each side with brackets indicated at 14, 80 which support between them a shaft 15. The shaft is located substantially close to the outer face of the door 10 and is provided at each end with a pendant swinging arm 16. These arms are provided at their lower ends 85 with weights 17 which normally hold the arms in true vertical position. Each arm near its upper end is provided with a forwardly projecting rest 18, which limits the downward swinging movement of a pawl 90 or finger 19 hingedly connected to the upper end of the arm. The fingers 19 normally project forwardly in horizontal direction and when the car ascends, engage the brackets or ledges 20 secured to the outer 95 face of door 10 at the sides and near the bottom thereof. After the fingers or pawls are thus engaged, further upward movement of the car will cause the door 10 to be lifted.

When the car stops opposite the doorway, 100 the door will be held in raised position, and when it is desired to further ascend, the car is moved upwardly. The upper end of the door engages the upper end of its guideway and further upward movement of the door 105 is arrested. Continued upward movement of the car will then cause the pawl 19 to swing the arm 16 rearwardly until the pawl be-

comes disengaged from the element 20. The weight 17 at once causes the arm 16 to swing back to normal vertical position, and the said arm is limited against swinging too far 5 forwardly by the chain 21 connecting the arm with the bracket 14. When the elevator descends, the pawl 19 engaging the element 20 is free to move upwardly, and the pawl therefore plays idly over the said 10 element.

The car 6 is provided near its lower end and upon the sides thereof with a pair of relatively short stub shafts 22, upon each of which is swingingly mounted a pawl or finger 15 23. The rear end of each finger is provided with a laterally disposed stem or rod 24, to which is swingingly connected the lower end of a connecting link or rod 25. The upper ends of these links are attached 20 to stems 26 projecting laterally from the upper ends of arms 16.

The weights 12 which act as counterbalances for the elevator door are each equipped with a hinged plate 27, and these plates are 25 arranged upon the tops of the weights so as to project forwardly beyond the same. The free ends of these plates are disposed in the path of travel of the fingers 23, and are designed to be engaged by the said fingers 30 when the elevator is descending to cause the weights 12 to move downwardly. This movement of the weights obviously causes the door 10 to slide upwardly. When the upper end of the door 10 has reached the 35 upper limit of its movement or when the weights 12 are limited against further downward movement, the fingers 23 will rock upon their stub shafts 22, causing the links 25 to swing the arms 16 rearwardly and lifting the weights 17.

It is obvious from the foregoing that I have provided an apparatus which is of extremely simple construction and which will positively actuate automatically when the 45 car ascends or descends.

The foregoing description and the drawings have reference to what may be considered the preferred or approved form of my invention. It is to be understood that I may 50 make such changes in construction and ar-

rangement, and combination of parts, materials, dimensions, etc., as may prove expedient and fall within the scope of the appended claims.

Having thus fully described my invention, 55 what I claim as new and desire to secure by Letters Patent is:—

1. The combination with a car and a door movable in the same direction; of a shaft on 60 said car, a pair of arms swingingly mounted on said shaft, weights at the lower ends of said arms, a ledge on the upper edge of each arm, a finger swingingly mounted upon each arm and designed normally to rest in horizontal position upon said ledges, and 65 catch elements secured to the outer face of the door and in the path traversed by said fingers.

2. The combination with a car and a door movable in the same direction; of a pair of 70 brackets upon said car, a shaft connecting said brackets, arms swingingly mounted upon said shaft at the ends thereof, weights at the lower ends of said arms, chains for limiting the swinging movement of said 75 arms in one direction, a ledge near the upper end of each arm, a pawl pivoted upon each arm and resting normally upon said ledge, a catch member upon the door and lying in the path traversed by said pawls, 80 fingers swingingly mounted upon said car near the lower end thereof, a link connecting each arm with the rear end of its adjacent finger, and a catch member associated with the elevator door and lying in the path 85 traversed by said fingers.

3. The combination with a car and a door; of pawls on said car one designed to engage the door and to open the same when the car ascends and the other designed to close the 90 door when the car descends, a weight normally holding one of said pawls in operative position, and a link connecting the said weight with the other of said pawls.

In testimony whereof I affix my signature 95 in presence of two witnesses.

SAM EVERSEN.
